UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed October 2, 1924. Serial No. 741,152.

To all whom it may concern:

Be it known that I, HARRY A. DAVIS, a citizen of the United States, and a resident of Hopedale, in the county of Worcester and State of Massachusetts, have invented an Improvement in Warp Stop Mechanisms for Looms, of which the following description, in connection with the accompanying drawings, is a specification, like characters 10 on the drawings representing like parts.

This invention relates to warp stop mechanisms for looms whereby the operative condition of the loom is changed when a warp thread breaks or becomes too slack 15 for weaving purposes.

The accumulation of lint on the main parts of the warp stop mechanism is a source of trouble in warp stop mechanisms and frequently becomes so serious that 20 proper operation of the warp stop mechanism fails and the loom continues to run even when a warp thread breaks or becomes too slack for weaving purposes.

In that type of warp stop mechanism 25 wherein the detector is given a reciprocating movement and is arrested in this movement by a drop wire when a warp thread becomes abnormally conditioned, the momentum of movement of the detector frequently causes injury to the drop wires. This is due, among other causes, to the rate 30 of travel or speed of the detector—the higher the speed of travel, the more liable will be injury to the drop wire which arrests movement of the detector.

One of the objects of the present invention, therefore, is to provide a warp stop mechanism of simple and effective character wherein the parts are so arranged that 40 lint may not accumulate thereon but will be shed or fall from the parts of the warp stop mechanism without interfering with the proper operation thereof.

Another important feature of the present invention consists in imparting to the detector a relatively slow movement, to the end that when it is arrested by a drop wire the momentum of the detector will not injuriously affect the drop wire and the loom 45 will be brought to rest.

Other features of the invention and new combination of parts will best be made clear from the following description and the accompanying drawings of one good form 50 thereof.

In the drawings:

Fig. 1 is a side elevation, partly in section, of a loom provided with the present invention;

Fig. 2 is a sectional detail of means for 60 knocking off or stopping the loom by the backward movement of the lay;

Fig. 3 is an enlarged detail and sectional view of portions of the stopping mechanism; 65

Fig. 4 is an enlarged cross-sectional view of the main portions of the warp stop mechanism;

Fig. 5 is an elevation showing a portion 70 of the main parts of the warp stop mechanism;

Fig. 6 is a perspective view of the main portions of the warp stop mechanism;

Fig. 7 is an enlarged detail showing the detector frame and the detectors secured 75 thereto in edgewise vertical position; and

Fig. 8 is a sectional detail showing more particularly the detector frame and its guiding support.

The loom frame 1 may be of any usual 80 construction and have associated therewith a means for stopping the loom when a warp thread breaks or becomes too slack for weaving purposes. In the present instance of the invention, as indicated in Fig. 1, the shipper 2 is normally held in the shipper notch, as usual, during weaving, and mounted upon the loom frame at 3 is a knock-off lever 4 to which is connected at 5 a rod 6 extending rearwardly into an opening of a 85 yoke 7 which may be conveniently pivoted at 8 to a rocker arm 9 supported from the loom frame at 10. In the opening 11 of the yoke 7 is a dog 12 normally under the influence of a light spring 13 for maintaining the dog in its inoperative position. 90

The lay 14 is provided with a bunter 15 which is adapted to engage the dog 12 when the latter is operatively positioned, the construction being such that when the 100 dog 12 is engaged by the bunter 15, as the lay moves back, the loom will be stopped.

Extending through the bracket member 16, Fig. 2, is the end 17 of a flexible wire 18 which is enclosed by a sheath 19, and the end of the part 17 rests against the dog 12, so that should the wire 18 be moved longitudinally, the dog 12 will be placed in operative position to be struck by the bunter 15 as the lay moves back, and thereupon 110

effect loom stoppage. The other end portion of the sheathed wire 18 is under the control of means connected to the warp stop mechanism for effecting endwise movement of the wire in its sheath when the warp thread breaks or becomes too slack for weaving purposes, as will more fully appear.

Adjustably mounted at the side of the loom frame is an arm 20, one of which is indicated in Fig. 6, and rising from the arm 20 is a stud 21 projecting into a socket 22 connected to one of the side brackets 23 of the main portion of the warp stop mechanism. The parts described are duplicated, one being at each side of the loom.

Mounted upon each of the side brackets 23 is a top plate 24 having open bearings 25 for the reception of the drop wire guides 26 which extend between the two brackets. Each of the drop wire guides 26 is provided with a washer 27 which is held pressed against the outside recessed portion 27* of the upstanding flange 28 by means of a spring 29 interposed between the washer 27 and the nut 30. The details of construction are clearly shown in Figs. 5 and 6. At its opposite end the drop wire guide 26 passes through the open slot 25 of the flange, and on the outside thereof is provided with a thumb nut 31 threaded to the end of the drop wire guide, the construction being such that by manipulation of the thumb nut 31 the drop wire guide may be tensioned under the action of the spring 29 and held yieldingly in position. Likewise, by manipulation of the thumb nut 31, the drop wire guide may be readily slackened and removed from the end supports for any purpose, such, for instance, as when a new set of warp threads is to be employed in the loom.

The drop wire guide 26 is thus supported between the side brackets in the open bearings for ready removal along with the drop wires. In the present instance, the drop wires 32 have the slots 33 through which the drop wire guide 26 passes, and such drop wire guides are positioned above the plane of the warp threads, as indicated in Fig. 4.

Obviously, any number of rows of drop wires and drop wire guides may be employed, but as shown in the present instance there are four rows of drop wires and drop wire guides, and the drop wires themselves are illustrated as of the hair pin type, a construction which lends to lightness in the weight of the drop wire, although other forms of drop wires may be employed.

Extending between the side brackets 23 are the guide bars 34 which are relatively spaced a sufficient distance apart for the lower end portions of the drop wires to freely move therein, and the spaces between the guide bars 34 are preferably such as to

permit any lint which may become detached from the warp threads *a* to drop down clear of interfering relation with the drop wires themselves.

In accordance with the present invention, 70 the detector is given a detecting movement below the drop wires, as indicated in Fig. 4, and, as shown, is supported for reciprocating movement. In carrying out this feature of the invention, the outside guide bars 34 75 have each secured thereto a bracket 35 between which extends a guide 36.

Mounted upon the detector guide 36 is the detector frame, which comprises the side members 37 extending downwardly about 80 the detector guide 36, as indicated in Figs. 7 and 8, the downwardly extending portions 37 being of sufficient extent to guide the detector frame upon the detector guide and to prevent the accumulation of lint thereon. 85 The downwardly extending portions 37 may conveniently be formed by bending the part connecting the two, as at 38, or the detector frame may be otherwise constructed.

Within the housing thus formed by the 90 part 38 are the rollers 39 which rest upon the detector guide 36, and afford anti-friction means to facilitate the movement of the detector guide. In the present instance of the invention there is a detector guide at 95 each side of the main parts of the warp stop mechanism, but any number of guides and detector frames may be employed in accordance with the width of the loom.

The detector guide is connected by a link 100 40 with an operating arm 41, as indicated in Fig. 4, which is secured to the rock shaft 42, which may itself be conveniently supported in brackets 43 carried by the main frame of the warp stop mechanism. As 105 shown in the present instance, the bearings 44 for the rock shaft 42 may be located one at each side of the warp stop mechanism. From the construction thus far described it will be apparent that upon rocking movement of the rock shaft 42 the detector frame 110 will be given its reciprocating movement.

Secured to the rock shaft 42 is a collar 45, Figs. 3 and 5, having a cam portion 46 which engages a complementary cam portion 115 47 carried by a collar 48 loosely mounted on the shaft 42. Between the collar 49 and the collar 48 is a spring 50 which yieldingly holds the complimentary cams 46 and 47 engaged, as indicated in Fig. 3. Extending 120 from the collar 48 is the arm 51 connected by the rod 52 to rock shaft actuating means, the construction being such that as long as the cams 46 and 47 are engaged, as indicated in Fig. 3, and no obstruction to the 125 rocking movement of the shaft 42 is encountered, the rock shaft, and through the described means the detector frame, will be given operative movement. Should, however, the detector frame be arrested, the rock 130

shaft 42 will be stopped, whereupon continuous actuation of the rod 52 will turn the collar 48 on the now fixed shaft, and the collar 48 will be moved longitudinally 5 on the shaft against the tension of the spring 50. Advantage is taken of this movement to effect loom stoppage.

Rising from the hub portion 53 of the arm 41 is a lug having a through-bearing 54, 10 Fig. 3, for the sheathed wire 18, the end of which bears against a plunger 55 which extends in substantial parallelism with the shaft 42 into a socket 56, Fig. 3, formed in the collar 48, so that should the collar 48 be moved longitudinally of the shaft, as hereinbefore described, it will effect movement of the sheathed wire 18 and through the dog 12 effect loom stoppage on the backward movement of the lay.

20 The detector frame has connected therewith the detector. In the present instance, the detector frame, one at each side of the warp stop mechanism, carries four detectors, each of which is arranged as a flat bar vertically disposed edgewise, so that any lint dropped on the detector or detectors will find no lodgement thereon, but will drop away from the warp stop mechanism.

In the present instance, the detector frame 30 has a cut-away portion at 57 affording shoulders 58 at each side thereof for a detector. At the end portions of the detector frame there are similar shoulder portions 59. Of course the number of shoulders on the detector frame will depend upon the number of detectors. In the present instance, each detector is formed of a flat bar 60 arranged edgewise vertically, as shown, and the upper surface at 61 is preferably rounded off to shed lint that may drop thereon.

40 The detectors may be connected to the detector frame by a through-bolt 62, as shown in Figs. 4 and 7. The through-bolt 62 passes through the housings 38, and suitable nuts 63 serve to secure the detectors on the detector frame in an edgewise vertical position, as described.

Should any lint drop from the warp threads or other source it will pass through the free space between the guide bars 34 and fall downwardly onto the detectors, but inasmuch as the detectors themselves are formed and secured as described, it will find no lodgement and consequently not interfere with the proper operation of the warp stop mechanism.

50 At the front and rear of the series of drop wires are the warp supports 64 over which the warp threads α pass. The ends of the warp supports 64 are held in bearings 65 which are preferably formed of wood which may be soaked in oil. The bearings 65 are carried by brackets 66 which may be adjustably held to the side frames 23 by means 65 of bolts 67 passing through slots 68 in the

side frame. As the warp threads travel over the warp supports, the latter may rotate with considerable freedom, since the warp supports are held in the lubricated wooden bearings.

70 In some instances it may be desirable to give additional support to the warp supports and drop wire guides, and such additional means may consist of wooden bearings 69, Fig. 6, between the ends of the warp supports and the intermediate bearings 70 for the drop wire guides. Such intermediate features, however, are not always necessary, but may be employed where the width of the loom requires it.

Owing to the detecting movement of the detector, as heretofore provided, the drop wires are frequently injured by the momentum of the detector.

80 The present invention provides, however, that the detector be given a slow detecting movement, so that should it contact with a drop wire, the momentum of the detector itself will not injure the latter. In the present instance of the invention, as indicated in Fig. 1, the actuating rod 52 extends downwardly and is connected with a lever arm 71 pivotally mounted at 72 and having a shoe 73 which bears upon the cam 74 under the impulse of the spring 75. Secured to or connected with the cam 74 is a gear 76 which may be driven from the under or cam shaft. The under or cam shaft 77 is driven from the crank shaft 78 in a one to two ratio. That is to say, the under or cam shaft 77 makes one revolution, while the crank shaft makes two. Secured to the under or cam shaft 77 is a gear 79 and between the gear 79 and the gear 76 is a reduction gear 80 which in the present instance makes one revolution to each two of the gear 79. The relation of the reduction gear 80 to the gear 76 is such that the latter makes one revolution to each two of the gear 80. From the construction described as a present embodiment of the invention, it will be apparent that the gear 76, and perforce the cam 74 which actuates the detector, will make one complete rotation to eight rotations of the crank shaft, and the detector will be correspondingly given a slow detecting movement.

90 As indicated in Fig. 1, the reduction gear 80 is supported in a bracket 81 having a slot 82 so that the size of the reduction gear 80 may be changed as circumstances may dictate.

100 The recesses 27* on the side brackets 28 are preferably formed to receive the engaging face of the collar 27, and are shown as rounded in order to prevent accidental detachment of the drop wire guides due to loom vibration and yet permit ready removal, as hereinbefore explained.

110 The detector has a reciprocating move-

ment preferably of greater amplitude than the distance between the rows of drop wires or the distance apart of the box plates 34, and the top of the detector is so closely adjacent to the bottom of the box plates 34 that during detecting movements of the detector any lint that may have lodged on the detector will be dislodged or wiped therefrom.

10. What is claimed is:

1. In a warp stop mechanism, the combination of a series of drop wires, a detector frame having side members, fixed guides for the detector frame enclosed by the side members, and flat drop wire detectors extending between the side members.

2. In a warp stop mechanism, the combination of guides secured in fixed position, a detector frame having side members in which said guides are housed to prevent accumulation of lint on the guides, a flat detector mounted edgewise in a vertical plane and having a rounded upper edge, and a series of drop wires normally supported by the warp threads during weaving.

3. In a warp stop mechanism, the combination of fixed guides, a detector frame having side members each provided with downwardly extending flanges and connecting top portions forming a housing for a fixed guide, a detector extending between the side members, and a series of drop wires normally supported by the warp threads during weaving.

35. 4. In a warp stop mechanism for looms, the combination of a series of drop wires normally supported by the warp threads during weaving, a drop wire guide yieldingly mounted at the side of the loom above the plane of the warp threads, guide bars at each side of the drop wires below the plane of the warp threads, a drop wire detector frame having a flat drop wire detector arranged edgewise in a vertical plane below the drop wires, means for reciprocating the detector frame horizontally, and means for stopping the loom when the detector frame is arrested in its reciprocating movement.

50. 5. In a warp stop mechanism for looms, the combination of a series of drop wires, brackets at each side of the loom having open slots, a drop wire guide extending between the brackets, a spring at one end of the drop wire guide exerting tension lengthwise of the drop wire guide, and means for adjusting the tension of the spring.

60. 6. In a warp stop mechanism for looms, the combination of a series of drop wires, brackets at each side of the loom having open slots, a drop wire guide extending between the brackets, a spring pressed collar

bearing upon the outside of the bracket at one end of the drop wire guide exerting tension lengthwise of the drop wire guide, and means for adjusting the tension of the spring.

7. In a warp stop mechanism, the combination of a series of drop wires, a bracket at each side of the loom, a drop wire guide extending between the brackets, a spring connected to the drop wire guide and exerting lengthwise tension on the drop wire guide and acting to retain the drop wire guide in guiding position.

8. In a warp stop mechanism for looms, the combination of a series of drop wires, a bracket at each end of the row of drop wires having an open slot, a drop wire guide extending between the brackets and resting in the open slots thereof, and a spring at one end of the drop wire guide outside the bracket exerting tension lengthwise of the drop wire guide and permitting ready removal of the drop wire guide.

9. In a warp stop mechanism for looms, the combination of a series of drop wires, a bracket at each end of the row of drop wires having an open slot, a drop wire guide extending between the brackets and resting in the open slots thereof, a spring at one end of the drop wire guide outside the bracket exerting tension lengthwise of the drop wire guide and permitting ready removal of the drop wire guide, and a member interposed between the spring and bracket at one end of the drop wire guide.

10. In a warp stop mechanism for looms, the combination of a series of drop wires, a drop wire guide, a loom cam shaft, a detector cam, a gear on the loom cam shaft, a gear secured to the detector cam, a bracket between the two gears having a slot for connection of different size change gears, and a change gear for transmitting movement from the cam shaft gear to the detector cam gear.

11. In a warp stop mechanism for looms, the combination of a series of drop wires, a detector frame having a series of flat detectors with top edges of less thickness than the body of the detector, means for securing the detectors edgewise in vertical position on the detector frame to shed lint, horizontal guides for supporting the detector frame, rollers housed from lint between the guides and detector frame, means for reciprocating the detector frame, and means for stopping the loom when the detector frame is arrested.

In testimony whereof, I have signed my name to this specification.

HARRY A. DAVIS.
